UNITED STATES PATENT OFFICE.

EUGENE D. ALLEN, OF DETROIT, MICHIGAN.

DESIGN FOR A LIGHTING-STANDARD.

46.985.

Specification for Design.

Patented Feb. 23, 1915.

Application filed February 18, 1914. Serial No. 819,580. Term of patent 3½ years.

To all whom it may concern:

Be it known that I, EUGENE D. ALLEN, a citizen of the United States, residing at Detroit, in the county of Wayne and State of Michigan, have invented a new, original, and ornamental Design for Lighting-Standards, of which the following is a specification, reference being had to the accompanying drawing, forming part thereof.

The figure is a perspective view of a lighting-standard showing my new design.

I claim:

The ornamental design for a lighting-standard as shown.

EUGENE D. ALLEN.

Witnesses:

DAVID N. HARPER,

LULU SEIFERT.
